UNITED STATES PATENT OFFICE.

BERNIS M. SHIPLEY, OF DAYTON, OHIO, ASSIGNOR TO THE NATIONAL CASH REGISTER COMPANY, OF DAYTON, OHIO, A CORPORATION OF MARYLAND.

CASH REGISTER.

Application filed August 10, 1926. Serial No. 128,450.

This invention relates to cash registers and the like, and has more particular relation to the type of machine shown and described in Letters Patent of the United States to Frederick L. Fuller, No. 1,242,170, issued October 9, 1917, and No. 1,394,256 issued on October 18, 1921.

The principal object of this invention is to provide a novel means for preventing the release shaft of the machine from being overthrown and thereby accidentally releasing the amount and transaction keys during repeat operations.

Another object is to provide a novel means for disabling the overthrow preventing device during total taking operations.

With these and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said drawings:

Fig. 1 is a right-hand side elevation of the machine and shows the mechanism for rocking and controlling the extent of movement of the release shaft.

Fig. 2 is a detail view showing a fragmentary portion of the total-taking lever and some of the mechanism associated therewith.

Fig. 3 is a detail view of the machine release pawl.

Fig. 4 is a detail view of a part of the mechanism for controlling the release of the machine.

Fig. 5 is a detail view of an amount bank of keys.

Fig. 6 is a detail view of a transaction bank of keys.

Fig. 7 is a detail view of the manual means for releasing the amount and transaction keys.

Fig. 8 is an enlarged detail of the mechanism for controlling the release shaft.

Fig. 9 is a rear view showing the release control yoke and arm, and the supports therefor.

In general.

The mechanism shown and described here-

in is an improvement of the mechanism shown and described in the co-pending application for Letters Patent, Serial No. 42,458, filed July 9, 1925, by Bernis M. Shipley, the present inventor.

The machine may be provided with any number of banks of amount keys and one or a plurality of banks of transaction keys, one bank only of amount keys and one bank only of transaction keys being shown. The transaction keys are provided for selecting totalizers, such as shown in the above mentioned application, into which the amounts set up by the amount keys are added. In some lines of business it is desired to repeat the addition of the amount set up on the keyboard a number of times on certain totalizers, but only once on other totalizers. In the present application a mechanism is provided by means of which such repeat operations are performed without the necessity of again depressing either the amount or transaction keys. When a transaction key is depressed, which automatically prevents release of keys, a mechanism is controlled whereby the machine release mechanism is restored to normal, but not past normal and therefore the keys will not be released. By very rapid operation of the machine it may be possible, without the structure of the present invention, to overthrow the key release shaft, thereby causing the keys, or some of them, to be released, thus making it necessary to again depress the keys, or, if only some of the keys have been released and the operator does not notice it, causing an incorrect addition to be made upon the repeat operation. In order to prevent such a possible overthrow of the key release shaft a mechanism to control the key release mechanism for repeat operations is automatically rocked into operative position upon depression of a transaction key.

All of the transaction keys control the selection of totalizers during both adding and total taking operations. When taking a total from one of the totalizers selected by a transaction key, which controls the machine for repeat adding operations, it is never necessary to prevent the release of the key. Therefore means is provided to disable the overthrow preventing mechanism of the key release shaft to keep said mechanism from

moving into its effective position during total taking operations. This mechanism is under control of the total taking lever.

Detail description.

Amount key bank.—The machine has a plurality of banks of amounts keys 30 for controlling differentials for adding the amounts into the selected totalizers. Depression of an amount key cams a detent 31 (Fig. 5) downwardly until a flattened stud 32 thereon engages above a shoulder 33 on the key, thereby holding the key in depressed position. The detent 31 is held in its home position by means of a spring 34 stretched between the key frame and an arm 35 pivoted at 43 on the key frame. Said arm 35 carries a stud 36 engaging an arm 37, upon which the lower end of the detent is pivoted. The upper end of the detent is pivoted on an arm 38 having a rearwardly extending tail 39. A rod 40, carried by a plurality of arms 41 (only one being shown) secured to a release shaft 42, engages the tail 39 near the end of the operation of the machine to move the detent 31 downwardly to disengage the flattened stud 32 from the shoulder 33, thereby releasing the depressed amount keys 30. The means for rocking the release shaft 42 will be herein-after described.

Transaction bank.—The machine may be provided with one bank or a plurality of transaction keys 50 (Fig. 6) which are adapted to control the selection of totalizers such as is illustrated and described in the above mentioned Shipley application. Each bank is provided with a detent 51 which cooperates with studs 52 on the transaction keys to hold the transaction keys in their depressed position. Each detent 51 is movably supported on arms 53 and 54. The arm 54 is provided with a tail 55 with which an arm 56 on the release shaft 42 cooperates to release the transaction key near the end of the operation of the machine in a manner to be later described.

Machine release mechanism.—The machine release mechanism is well known and is fully illustrated and described in the previously mentioned Shipley application and in Letters Patent of the United States No. 1,602,596, granted to B. M. Shipley, the present inventor, on October 12, 1926. A motor key 60 (Fig. 1) is provided to release the machine for operation. In order to release the machine a pawl 61 (Fig. 3) must be rocked from the path of a flattened stud 62 on an arm 63 secured to the release shaft 42. A spring 64, (Figs. 1 and 8) one end of which rests against a shoulder on a link 65, and the other end of which bears against a clip attached to an arm 66 secured to the release shaft 42, constantly tends to rotate the shaft 42 in a clockwise direction but is prevented from doing so by the pawl 61. The pawl 61 (Fig. 4) is disengaged from the stud 62 by the motor key

60, through a stud 67 (Fig. 1) engaging a lever 68 pivoted on the side frame 69. Upon depression of the motor key 60 the lever 68 rocks an arm 70 (Fig. 4), yoked to an arm 71 which engages a stud on an arm 72. The arm 72 is yoked to a bifurcated arm 73 (Fig. 3), engaging a stud on the pawl 61. Therefore, rocking of the arm 70 rocks the bifurcated arm 73 in a clockwise direction to disengage the pawl 61 from the stud 62, thus permitting the spring 64 (Figs. 1 and 8) to rock the release shaft 42 in a clockwise direction to release the machine.

Key release mechanism.—After the machine has been released, a main cam shaft 80 (Fig. 1) is given one complete rotation in the direction shown by the arrow in Fig. 1, by any suitable driving means, such as a motor clutch, as illustrated and described in the Letters Patent of the United States No. 1,619,796, issued to the present applicant on March 1, 1927; said clutch being adapted to be connected with a motor such as shown and described in the patent to Charles F. Kettering and William A. Chryst, No. 1,144,418, issued on June 29, 1915. Secured to the shaft 80 is a gear 81 meshing with a gear 82. The ratio of the gears 81 and 82 is such that the gear 82 is given a one half rotation for each full rotation of the gear 81. The gear 82 is provided with a race having two cams 83, engaging said race is a roller 87 carried by a lever 84, pivoted on the frame 69. Said lever also carries a stud 85 engaging a slide 86 (Figs. 1 and 8), supported on stud 88 on the link 65. On each full rotation of the shaft 80 and half rotation of the gear 82, one of the cams 83 rocks the lever 84 clockwise and then counter-clockwise. The clockwise movement of said lever 84, through the stud 85 and slide 86, lowers the link 65, thereby rocking the release shaft 42 in a counter-clockwise direction to normal position to restore the arm 63 (Fig. 3), and still farther past normal to cause the rod 40 (Fig. 5) to engage the tails 39 to release the amount keys, as above described. This movement of the release shaft 42 past its normal position also engages the arm 56 (Fig. 6) with the tail 55 of the arm 54, thereby releasing the transaction keys.

Repeat operations.—Certain of the transaction keys 50 are adapted to control the slide 86 (Figs. 1 and 8) in such a manner that when the machine is operated the slide will be disengaged from the stud 85, and therefore the lever 84 will move idly until its stud 85 engages a shoulder 90 on the link 65; whereupon the link will be lowered, but this time only far enough to restore the arm 63 (Fig. 3) to permit the release pawl 61 to again assume its normal position in front of the stud 62. This movement of the shaft 42 is not far enough to rock the rod 40 and the arms 56 into engagement with their respective detent arms and consequently the keys 30 and 50

are not released. Any number of keys 50 may be adapted to control this slide 86. However, in the present application, for purposes of illustration only, the six lower keys 50 are shown as adapted to control said slide 86. The three upper keys have no effect upon the slide 86 and therefore when the machine is operated with any of these three keys depressed the slide 86 remains in the normal position and therefore upon operation of the machine the lever 84, through its pin 85 and the slide 86 lowers the link 65 and rocks the shaft 42 and the amount and transaction keys are released.

15 Adjacent to the bank of transaction keys 50 (Fig. 6) is a lever 91 having inclined edges 92 co-operating with the pins 52 of the transaction keys for rocking the lever 91. This lever 91 (Fig. 6) has an integral arm 20 89 carrying a pin 100 engaging a slot 101 in an arm 102, connected by a yoke 93 to an arm 103. The arm 102 is pivoted on a shaft 104 (Fig. 9) supported by two of the usual differential hangers 111, and the arm 103 is pivoted on a stud 112 in the frame 69. The arm 103 carries a stud 94 adapted to engage an arm 95 of a lever 96 pivoted on the link 65. The lever 96 is bifurcated to engage a projection 98 on the slide 86 and is adapted to hold 25 the slide 86 in the position shown by means of a spring 99. Depression of one of the lower keys 50, by means of the lever 91 and arm 89 rocks the arms 102 and 103 counter-clockwise and causes the stud 94 to engage 30 the arm 95 and rock the lever 96, thereby moving the slide 86 toward the left (Fig. 8), thus disengaging it from the stud 85. Upon subsequent operation of the machine the stud 85 will engage the shoulder 90 of the link 65, thereby restoring the release shaft to its 35 home position, as above mentioned, but not far enough to release the amount and transaction keys.

Release shaft overthrow preventing means.—

40 If the machine should be operated too rapidly, it is possible to cause the release shaft 42 to be rotated past its normal or home position during the repeat operations, thereby accidentally causing the amount and transaction keys to be released. In order to prevent this, the arm 66 (Figs. 1 and 8) is provided with a shoulder 105 into the path of which an arm 106 is rocked when any one of the lower transaction keys 50 is depressed. 45 The arm 106 tends to rock into the path of the shoulder 105 due to a spring 107, but is prevented from doing so by a stud 108 mounted on a bell crank 109 which is connected to the arm 106, and by a stud 110 mounted on the link 65. Therefore, in order that the overthrow preventing arm 106 may be rocked into the path of the shoulder 105 on the arm 66, it is necessary to remove the slide 86 away from the stud 108 on the bell crank 109 and also move the stud 110 away

from the bell crank 109. When the slide 86 is moved toward the left upon depression of any of the lower transaction keys, as above described, the spring 107 will tend to rock the arm 106 into the path of the shoulder 105 of the arm 66. However, the bell crank 109 is held against movement at this time by the stud 110, but during the operation of the machine, when the link 65 is lowered, the bell crank 109 is permitted to move, thereby rocking the arm 106 into the path of the shoulder 105. The arm 106, therefore, provides a stop for the arm 66 when the arm 66 arrives at its normal position, in which position the pawl 61 is free to rock into the path of the flattened 50 stud 62, thereby stopping the machine. Near the end of the upward movement of the link 65, the stud 110 engages the arm 109, thereby disengaging the arm 106 from the shoulder 105.

55 *Manual key release.*—After a series of repeat operations have been made it is sometimes desirable to release the amount and transaction keys, for example, when it is desired to take a total or set up new amounts. 60 In order to permit this release of the keys the well known manual key release has been provided. This release consists of a lever 115 (Fig. 7) which has a projection 116 co-operating with a stud 117 on a link 118 for 65 rocking an arm 119 on the release shaft 42. The lever 115 is held in its normal position by a spring 120. This manual release is well known in the art and therefore no further description will be given herein.

70 *Total taking operations.*—All of the transaction keys 50 control the selection of totalizers during adding operations. These keys also select totalizers during total taking operations for printing the totals thereon. However, during total taking operations, repeat operations are never necessary, and therefore the transaction keys must be released during 75 every total taking operation. For this reason it is necessary to provide some means for preventing the arm 106 from moving into the path of the shoulder 105 of the arm 66 when one of the lower transaction keys is depressed for total taking operations, inasmuch as the key release shaft 42 is always rocked far enough to release the depressed transaction 80 keys during total taking operations.

85 A total lever 125, (a part of which is shown in Fig. 2), controls the link 65 in a manner whereby the stud 85 will engage a shoulder 126 during total taking operations, thereby rocking the shaft 42 far enough to release the transaction keys. This movement of the lever 65 is effected by means of a cam slot 127 (Fig. 2) which rocks an arm 128 which by means of a spring 129 rocks an arm 130 in a counter-clockwise direction when the total lever is moved out of its add position. The arm 130 is provided with a cam slot 131 which rocks an arm 132 secured to a shaft 133. Also 90

secured to the shaft 133 is an arm 134 (Fig. 1), which is adapted to rock an arm 135 by means of a link 136. The arm 135 operates a pitman 137 connected to the link 65 by means 5 of a stud 138. From this it is apparent that when the total lever 125 is moved out of its adding position the lower end of the link 65 will be moved toward the left. This movement disengages the slide 86 from the stud 85 and positions the shoulder 126 into the path of the stud 85. During total taking operations the gear 82 makes a complete rotation. Therefore the arm 84 is given two 10 oscillating movements during total taking operations. However, it is desired to maintain the transaction key depressed until near the end of the operation, and for this reason a 15 cut-away portion 139 (Figs. 1 and 8) of the link 65 is moved into the path of the stud 85 during the operation of the machine. The pitman 137 has a roller 140 which is moved into a cam slot 141 when the total lever is moved out of its add position. This cam slot is so 20 formed that during the first half of the rotation of the gear 82 the lower end of the link 65 is moved to the left far enough to position the cut away portion 139 into the path of the stud 85. Before the arm 84 receives its second oscillation, the cam 141 moves the 25 link 65 back toward the right, and positions the shoulder 126 into the path of the stud 85. Then, upon second movement of the lever 84, the stud 85 engages the shoulder 126, thereby 30 restoring the release shaft 42 and moving it far enough past its home position to release the transaction keys.

The pitman 137 has mounted thereon a 40 stud 150 for preventing the arm 106 from moving into the path of the shoulder 105 of the arm 66 during total taking operations. The bell crank 109 is provided with a forwardly extending arm 151 with which the stud 150 is adapted to engage when the total lever 125 is moved out of its adding position. 45 Upon depression of one of the lower keys 50, after the total lever has been moved out of its add position, the slide 86 will be moved toward the left, but the bell crank 109 cannot follow because the arm 151 engages the stud 55 150 and therefore the arm 106 is prevented from moving into the path of the shoulder 105. Thus, during every total taking operation the release shaft will be free to move far enough to release the transaction key.

55 While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope of the claims which follow.

What is claimed is:

60 1. In a machine of the class described, the combination of a release shaft, means for

either returning said shaft to normal or past normal position, manipulative devices for determining the extent of movement of the release shaft, and means operated under control of said devices for preventing accidental movement past normal when said release shaft is to move only to its normal position. 70

2. In a machine of the class described, the combination of a plurality of amount keys, a release shaft for releasing said keys at the 75 end of the operation of the machine, a plurality of transaction keys for determining the extent of movement of said shaft thereby determining whether the amount keys shall be released, and means also controlled by 80 said transaction keys for preventing the shaft from accidentally moving far enough to release the amount keys when the amount keys are not to release.

3. In a machine of the class described, the 85 combination of a plurality of amount keys, a plurality of transaction keys, a release shaft for releasing all of said keys, means controlled by a transaction key to prevent the release shaft from releasing any of said keys, 90 and means also controlled by said transaction key for preventing overthrow of the release shaft past normal position.

4. In a machine of the class described, the combination of a machine releasing means, a 95 manipulative device for permitting said means to operate, means for returning said means either back to normal for stopping the machine at the end of the operation of the machine or past normal, a plurality of manipulative devices for controlling the extent of movement of said releasing means, and a device under control of said manipulative devices for preventing overthrow of the releasing means when said releasing means is returned back to normal for stopping the machine. 100

5. In a machine of the class described, the combination of machine releasing means, amount determining devices, a manipulative 110 device for permitting said means to operate, members operated by the releasing means for releasing the amount determining devices, means for returning said releasing means either back to normal for stopping the machine or past normal for releasing said amount determining means, and a device controlled by the returning means for preventing overthrow of the releasing means when said releasing means is to be only returned 115 back to normal for stopping the machine thereby preventing accidental release of said manipulative devices.

6. In a machine of the class described, the combination of a plurality of transaction devices, means controlled by the transaction devices for preventing release thereof during adding operations, means for preventing accidental release of the transaction devices, a manipulative device, and means intermediate 120

130

the second mentioned means and said manipulative device and controlled by said manipulative device for preventing the second mentioned means from becoming effective during total taking operations.

7. In a machine of the class described, the combination of a plurality of transaction devices, means controlled by the transaction devices for determining whether the transaction devices will be released at the end of an adding operation, means controlled by the transaction devices for preventing accidental release of the transaction devices upon operation of certain of the devices, a manipulative device for controlling the machine for total taking operations, and means adapted to cooperate with said preventing means and controlled by said manipulative device for preventing the second mentioned means from becoming effective during total taking operations.

8. In a machine of the class described, the combination of a plurality of transaction devices, means controlled by the transaction devices for determining whether the transaction devices will be released at the end of an adding operation, means controlled by the transaction devices for preventing accidental release of the transaction devices upon operation of certain of the devices, a member for causing the transaction devices to always release during total taking operations, and means controlled by the member for preventing the last mentioned means from becoming effective during total taking operations.

9. In a machine of the class described, the combination of a release shaft, a cam for returning said release shaft to or past its home position, an arm having a shoulder on the release shaft, and a spring actuated arm having a shoulder adapted to be rocked into the path of the shoulder of the first mentioned arm when the release shaft is to move only to its home position thereby preventing overthrow of the release shaft.

10. In a machine of the class described, the combination of a plurality of amount keys, a release shaft for said keys whereby the keys are released at the end of the operation of the machine, a plurality of transaction keys, a cam for operating said release shaft, a slideable member controlled by the transaction keys for determining the extent of movement the release shaft receives from the cam, an arm on the release shaft having a shoulder, and a spring actuated arm having a shoulder adapted to be rocked into the path of the shoulder of the first mentioned arm, said spring actuated arm being controlled by the slideable member for preventing overthrow of the release shaft and accidental release of the amount and transaction keys.

11. In a machine of the class described, the combination of a plurality of transaction keys, a machine release shaft, a key for re-

leasing the shaft, an arm having a definite movement, a link connecting said arm and said shaft, and a slideable member controlled by certain of the transaction keys for disconnecting said link from said arm for preventing movement of the release shaft far enough to release the transaction keys during adding operations.

12. In a machine of the class described, the combination of a plurality of amount keys, a plurality of transaction keys, a machine release shaft, a rod operated by the release shaft for releasing said amount and transaction keys, a key for releasing the shaft, an arm having a definite movement, a link operated by said arm, a slideable member controlled by certain of the transaction keys for disconnecting said link from said arm for preventing movement of the release shaft far enough to release the transaction and amount keys thereby permitting repeat operations, an arm on said shaft having a shoulder, and another arm controlled by said slideable member to cooperate with the arm on the shaft to prevent overthrow of the release shaft thereby preventing accidental release of the amount and transaction keys during repeat operations.

13. In a machine of the class described, the combination of a plurality of amount keys, a plurality of transaction keys, a machine release shaft, a rod operated by the release shaft for releasing said amount and transaction keys, a key for releasing the shaft, an arm having a definite movement, a link operated by said arm, a slideable member controlled by certain of the transaction keys for disconnecting said link from said arm for preventing movement of the release shaft far enough to release the transaction and amount keys thereby permitting repeat operations, an arm on said shaft having a shoulder, another arm controlled by said slideable member to cooperate with the arm on the shaft to prevent overthrow of the release shaft thereby preventing accidental release of the amount and transaction keys during repeat operations, a total lever, a slide adapted to be shifted by the total lever for controlling the position of said link during total taking operations whereby the amount and transaction keys will always be released, and a stud on the slide adapted to prevent the second mentioned arm from cooperating with the shoulder on the first mentioned arm during total taking operation so that the release shaft will always release the transaction keys at the end of a total taking operation.

14. In a machine of the class described, the combination of a release shaft adapted to be moved to release the machine and also adapted to be moved back to and past normal position, means for moving said shaft in the manner stated, a series of manipulative devices, and means controlled by certain of said de-

VICES to prevent said moving means from moving the release shaft past normal position when any one of said certain devices is operated.

5. 15. In a machine of the class described, the combination of a plurality of amount keys, a plurality of transaction keys, a release shaft

for releasing all of said keys, and means controlled by certain of said transaction keys to prevent the release of any of the amount ¹⁰ and transaction keys and to stop said release shaft in its normal position.

In testimony whereof I affix my signature.
BERNIS M. SHIPLEY.
